UNITED STATES PATENT OFFICE.

VINCENT F. MALISZEWSKI, OF DETROIT, MICHIGAN, ASSIGNOR OF FIVE ONE-HUNDREDTHS TO WALTER KRAJEWSKI, OF DETROIT, MICHIGAN.

SHIP-PROTECTOR.

1,261,829.

Specification of Letters Patent. Patented Apr. 9, 1918.

Application filed September 27, 1917. Serial No. 193,449.

To all whom it may concern:

Be it known that I, VINCENT F. MALISZEWSKI, a citizen of the United States, residing at Detroit, in the county of Wayne and

5 State of Michigan, have invented certain new and useful Improvements in Ship-Protectors, of which the following is a specification.

The primary object of this invention is the 10 provision of a protector for ships whereby missiles of any form will be prevented from hitting the ship, the protector being composed of non-explosive and non-combustible material.

15 A further object of the device is the provision of a slightly resilient substantially enveloping missile protector for ships so arranged as not to impede the travel of the ship but capable of protecting substantially

20 all portions thereof against injury from oncoming missiles such as torpedoes and bombs.

With these general objects in view and others that will appear as the nature of the 25 invention is better understood, the same consists in the novel construction, combination and arrangement of parts hereinafter fully described, illustrated in the accompanying drawings and pointed out in the appended 30 claim.

In the drawings forming a part of this application and in which like numerals refer to corresponding parts throughout the several views.

35 Figure 1 is a side elevation of a ship provided with the present device, the device being shown in vertical longitudinal section.

Fig. 2 is a top plan view thereof.

Fig. 3 is a horizontal section through the 40 upper portion of the ship with the upper portion of the device removed.

Fig. 4 is a vertical transverse sectional view of Fig. 1.

Fig. 5 is a perspective view of a portion 45 of one side section of the device and

Fig. 6 is a perspective view of a side portion of the hull.

Referring more in detail to the drawings, a ship is herein illustrated having a hull 10, 50 deck 11 and cabin 12, an enveloping protector 13 being arranged around and attached to the hull 10 and provided with an upper inclosing top portion 14 arranged thereon, whereby the entire ship is substantially surrounded by the device.

The hull protector 13 is preferably formed of two side sections 15, a rear section 15^a, and a prow section 15^b arranged around and beneath the hull, each of the said sections being provided with inwardly projecting 60 supporting hooks 16 adapted for reception within correspondingly positioned sockets 17 carried by the hull 10. The said section 15^a is cut away at the rear ends thereof as at 18 to accommodate the propeller 19 and the 65 rudder 20, the prow member 15^b having a cutter or guard member 21 at the front end thereof. Retaining latches 31 are carried by the deck 11 adapted for swinging outwardly 70 over the sections 15, 15^a, 15^b to hold hooks 16 seated in their sockets 17. A non-explosive and incombustible filling 32 is arranged within the protector member 13 contacting the hull 10.

The top 14 is in the form of a cap seated 75 upon the upper edges 22 of the bottom protector members 15, 15^a, 15^b, and is arranged with a desirable number of port holes 23 and doors 24. The pilot house 25, the funnels 26 and the wireless apparatus 80 27 are arranged to project through the top member 14.

The sections of the protector heretofore noted are formed of spaced inner and outer sides of metallic screen or fabric 28 filled or 85 stuffed with a cushioning means 29 which is preferably non-explosive and incombustible such as mineral wool, asbestos, or the like, and the sections may have a centrally disposed metallic reinforcing plate 30 (see Fig. 90 5).

It will be understood that when the ship is provided with the lower protector 13 and the top protector 14, any missile directed toward the ship will explode against the protector without damaging the hull of the ship, and without endangering the ship's hull by starting a fire, since the protector will neither explode nor burn. The protector being light in weight permits the ship to move 100 freely during the travel thereof and by reason of the spacing of the device 13 from the hull of the ship, a resilient buffeting receiver is arranged to catch any missiles.

What I claim as new is:—

In combination with the hull of a ship, a protector comprising a hull protector embodying a pair of side-sections, a rear section, and a prow section, said sections disposed around the hull of the ship with their 110

upper edges on a plane with the deck of the ship, sockets carried by the ship's hull, hook-arms carried by the sections having their inner ends seated in said sockets, retaining latches carried by the deck of the ship overlying and engaging the upper edges of the said sections to hold the hook-arms in seated engagement in the sockets, and a hood or top

section supported on the upper edges of the hull-protecting sections.

In testimony whereof I affix my signature in presence of two witnesses.

VINCENT F. MALISZEWSKI.

Witnesses:

B. F. DOMZALSKI,
MARION JOZEFIAK.
